ROTARY PRINTING PRESS

Edward R. Harena, Chicago, Ill., assignor to Miehle-Goss-Dexter, Incorporated, Chicago, Ill., a corporation of Delaware

Filed Apr. 13, 1964, Ser. No. 79,479

Term of patent 14 years

(Cl. D64—11)

FIGURE 1 is a perspective, from the driving side, showing a rotary printing press embodying the new design;

FIG. 2 is a side elevation of the rotary printing press shown in FIG. 1 as seen from the driving side;

FIG. 3 is a side elevation of the rotary printing press shown in FIG. 2 as seen from the operating side; and

FIG. 4 is a section taken approximately along the line 4—4 in FIG. 3.

This application is a continuation-in-part of my application Serial Number D. 72,096 filed October 12, 1962 and now abandoned.

I claim:

The ornamental design for a rotary printing press, substantially as shown and described.
